SYSTEM OF MERCURY VAPOR LIGHTING

Herman O. Stoelting, Milwaukee, Wis., assignor to
McGraw-Edison Company, a corporation of Delaware

Application January 17, 1955, Serial No. 482,017

9 Claims. (Cl. 315—122)

This invention relates to lightning protecting means for series circuit mercury vapor lamps.

In series systems of mercury vapor lighting damage from lightning frequently occurs. This damage may be to the film cut-out placed in parallel with each of the lamps or to the lamp itself due to the lightning surge. It is the usual practice to ground some portion of the series loop, for example, the middle portion or that portion most remote from the constant current supply means such as a constant current transformer for instance. Under these conditions it is apparent that when lightning strikes some portion of the circuit the surge is discharged at the grounded portion but has to travel past a number of mercury vapor lamps before it arrives at such grounded portion and consequently the various elements constituting the series loop are subjected to high voltages for a period measured in microseconds.

The film cut-out or puncturable film device is relatively inexpensive but it is a troublesome element to replace as it not only requires the services of a lineman but also because it is frequently placed in a rather difficultly accessible position, for example, in the lamp socket itself and thus requires a considerable amount of labor to replace it. The film cut-out itself is not very expensive but the time loss and the labor consumed constitutes a marked disadvantage.

Damage to the mercury vapor lamp itself by lightning is very objectionable as these lamps are relatively expensive.

Damage from lightning can occur either when the mercury vapor lamps are operating or when the circuit is deenergized. In both cases the lightning surge usually causes damage.

It is difficult to protect mercury vapor lamps due to the fact that they have a negative resistance current characteristic, the resistance falling as the current in the lamp increases. Thus it is difficult to generate sufficient voltage to cause sparkover for a protecting gap even if a protecting gap is placed in shunt with each lamp. Consequently voltage rise under these conditions usually causes puncture of the film cut-out if not damage to the lamp itself.

This invention is designed to protect mercury vapor lighting systems against damage from lightning strokes no matter whether the rate of rise of the surge current due to the lightning is rapid or relatively slow, and a further and highly desirable object, in the preferred form of the invention, is to provide such a type of lightning protection that it will not only protect the lamp itself but it will also protect the film cut-out while in no way interfering with the normal and desirable operation of the mercury vapor lamp or the film cut-out.

Further objects are to provide lightning protecting means for mercury vapor lamps which is relatively inexpensive and which may be easily installed and which occupies a relatively small amount of space.

It is immediately apparent that due to the increase in voltage drop across mercury vapor lamps with an in-

2

crease in rate of rise in surge current, that it is easier to protect the lamp by means of a spark gap during steep front surges than it is to protect the lamp for moderate rates of surge current rise. This invention however provides protection for either type of lightning surge current so that the lamp and the film cut-out as well, are both protected under all conditions irrespective of the type or rate of surge current rise as measured against microseconds, for instance.

10 A further specific object of this invention is to provide means for protecting mercury vapor lamps against damage from lightning under both conditions either when the lamp is operating or when the lamp is cold.

Embodiments of this invention are shown in the accompanying drawing in which:

Figure 1 is a diagrammatic view showing a mercury vapor series system with the invention applied thereto.

Figure 2 is an enlarged schematic detail of one of the units.

20 Figure 3 is a chart showing the relation between the voltage and time for a mercury vapor lamp sparkover when the lamp is cold, for a film cut-out, and for a lightning arrester spark gap, when the lightning protecting means is not used.

Figure 4 shows a series of curves indicating the rate of rise of surge current and voltage across a lamp when the lightning protecting means is not used.

Figure 5 shows a modified form of the invention.

Referring to the drawings it will be seen that a series system of mercury vapor lighting has been indicated, in Figure 1, and a single unit has been illustrated in Figure 2, the latter figure being drawn to an enlarged scale.

The mercury vapor lamps may be of any suitable type commonly used in series circuit lighting systems. One 35 form of commonly used mercury vapor lamp has a pair of main electrodes and a starting electrode closely spaced from a main electrode and connected to the other electrode through a high resistor of the order of several megohms for instance.

40 The mercury vapor lamps, indicated by the reference character 10, are connected in a series loop with some portion of the loop, for example, the outer portion or mid-point, indicated at 11, grounded as indicated at 12. The circuit is supplied from a high voltage source of 45 alternating current, such as a substantially constant current transformer T. The transformer is preferably a static type, constant current transformer. A moving coil type, though less desirable, can be used. The circuit is indicated by the reference character 13 and it will be seen that at each of the mercury vapor lamps a spark 50 arrester gap 14 and a film cut-out 15 are bridged across the lamp, or in other words are arranged in parallel with the mercury vapor lamp 10. However, it is to be noted particularly that an impedance such as the resistor 16 is placed in series relation to the mercury vapor lamp 10 and to the film cut-out 15. The spark gap however is not affected by the impedance or resistor 16 but is directly in the circuit independently of the impedance.

55 It is within the scope of this invention to form the spark gap 14, the film cut-out 15, and the impedance 16 as a unitary structure as indicated by the dotted lines 17 of Figure 2.

60 While the following figures are in no sense to be interpreted as limiting they are given so as to show clearly what has been successfully used for certain installations. For example, for a mercury vapor lamp requiring 135 volts while operating and a current of 3.2 amperes, it has been found that the impedance 16 may consist of a resistor of 1.5 ohms. It is again stated that 65 these figures are not to be interpreted as limiting but are merely to assist in giving a general picture of one particular installation.

It will be immediately appreciated that due to the increase in voltage drop across mercury vapor lamps with an increase in rate of rise of surge current, it is easier to protect the lamp by means of a spark gap across the steep front surges than against the more moderate of surge current rises. In order to protect a mercury vapor lamp against surges, the impedances 16 hereinabove described are placed in series with the lamps and film cut-outs so as to increase the voltage drop sufficiently to cause sparkover of the protecting gap 14. It is of course to be understood that the impedance may be an inductance, a capacitance, or several possible combinations and inductances or it may be a resistor. The preferred embodiment is a resistor as shown and described for the reason that an inductance while it does not cause a total loss of energy, has a voltage drop which is proportional to the rate of surge current rises. The inductance therefore has the highest voltage drop at the higher rates of surge current rise where it is not so much needed for protection and thus becomes most effective at the same time that the spark gap becomes most effective. On the other hand, a capacitor has an impedance which is roughly inversely proportional to the steepness of the front of the surge, somewhat analogous to the considerations affecting the impedance of the capacitor for high frequency phenomena. This type of characteristic while desirable for protection of mercury vapor lamps is not desirable for passage of the ordinary 60 cycles operating current, in the normal operation of the lamp, since a capacitor to be effective in lightning protection would cause an excessive voltage drop during normal operation. In addition to this both the inductance and the capacitor have to be many times larger in physical size than an effective and satisfactory resistor.

The spark gap contemplated by this invention would have to be so designed that it is unaffected by the discharge of surge current when followed by a power current flow not exceeding one-half cycle, for example, though variations in the design of the spark gap are of course contemplated by this invention. In other words, the spark gap would be so arranged that it would not be damaged under normal operating conditions.

In order to assist in a clear appreciation of the significance of the various components forming the lightning protecting means attention is directed to the curves shown in Figures 3 and 4. Figure 3 shows for curve X, the sparkover voltage plotted against time for the mercury vapor lamp while the lamp is cold or in non-operating condition. Curve X does not indicate the normal starting voltage of the lamp, but indicates the undesirable condition when there is a sparkover from one main terminal to the other. Figure Y shows the relation between the voltage and time for lightning protection with a film cut-out. Curve Z shows the relation between voltage and time for the spark gap.

Figure 4 illustrates the relation between the rate of rise of surge current and the voltage. The current is plotted in the reverse direction from the voltage merely for the sake of clearness in the diagram. It is to be understood that the voltage wave shape and crest magnitude of both the current and voltage are not well established because of the wide range in current wave shapes which are possible in a lightning surge. The figure is intended only to convey the idea that there is a definite relationship between the maximum voltage drop and the rate of rise of surge current. The voltage curves A, B, and C correspond to surge current curves A, B, and C. These curves shown in Figure 4 are for a mercury vapor lamp which is not equipped with the lightning protecting means forming the subject matter of this invention.

The curves shown in Figures 3 and 4 are not intended to be absolutely accurate under all operating conditions, but are curves obtained from laboratory measurements and are only relative. Due to variations in individual specimens of lightning arrester spark gaps, mercury vapor

lamps, and film cut-outs a more accurate representation would be by relatively wide bands rather than by single curves.

In the form of the invention shown in Figure 5, the impedance 16' is placed in series with the mercury vapor lamp 10 and not in series with the film cut-out 15 as in the previously described form of the invention. With this construction the film cut-out 15 would be subject to higher impulse voltages than with the circuit shown in Figure 2 but the proper operation of the circuit would still be possible and practical though the form of the invention shown in Figure 2 is much the preferred form. It is, however, to be distinctly understood that the form of the invention shown in Figure 5 is not considered 15 the equivalent of the form of the invention shown in Figure 2 and unquestionably the film cut-out 15 of Figure 5 is not protected in the same manner as that shown in Figure 2.

It will be seen that novel and extremely simple forms 20 of lightning protecting means have been provided by this invention which may be most easily used and installed in a series system of mercury vapor lighting.

It is to be noted particularly that though the constructions are extremely simple and the component parts relatively inexpensive that nevertheless these lightning protecting devices are eminently effective in protecting 25 against serious damage to the mercury vapor lamps, in both forms of the invention, and against inadvertent puncture of the film cut-outs as well, in the preferred form of the invention, during lightning surges.

Although this invention has been described in considerable detail, it is to be understood that such description is intended as illustrative rather than limiting, as the invention may be variously embodied and is to be 35 interpreted as claimed.

I claim:

1. A series system of mercury vapor lighting comprising a plurality of mercury vapor lamps connected in series in a main line, a source of high voltage alternating current, a 40 cut-out shunted across each mercury vapor lamp for shorting out any lamp upon failure thereof and constituting a parallel circuit with the corresponding lamp, an impedance connected in series with each parallel circuit and constituting therewith a compound circuit, and a spark 45 gap directly in series with said main line and bridging each compound circuit consisting of the series impedance and the parallel circuit.

2. A series system of mercury vapor lighting having a plurality of units connected in series in a main line and having a substantially constant current high voltage source, each unit consisting of a spark gap directly in series with 50 said main line and a parallel circuit bridging said spark gap and connected in series with an impedance with the impedance located between one end of the spark gap and one end of the parallel circuit, each of said parallel circuits consisting of a mercury vapor lamp and a bridging cut-out shunted across said lamp for shorting out the lamp upon failure thereof.

3. A series system of mercury vapor lighting having a 55 plurality of units connected in series in a main line and having a substantially constant current high voltage source and having a grounded portion, each unit consisting of a spark gap directly in series with said main line and a parallel circuit bridging said spark gap and connected in series with an impedance with the impedance located between one end of the spark gap and one end of the parallel circuit, each of said parallel circuits consisting of a mercury vapor lamp and a bridging cut-out shunted across said lamp for shorting out the lamp upon failure thereof.

4. A series system of mercury vapor lighting having a 70 plurality of units connected in series in a main line and having a substantially constant current high voltage source and having a grounded portion at a point remote from said source, each unit consisting of a spark gap directly in

series with said main line and a parallel circuit bridging said spark gap and connected in series with an impedance with the impedance located between one end of the spark gap and one end of the parallel circuit, each of said parallel circuits consisting of a mercury vapor lamp and a bridging cut-out shunted across said lamp for shorting out the lamp upon failure thereof.

5. A series system of mercury vapor lighting comprising a plurality of spark gaps connected in series, a separate circuit bridged across each spark gap, each circuit consisting of a parallel circuit including a mercury vapor lamp and a cut-out bridged across said lamp, and each separate circuit having an impedance connected in series with the parallel circuit between one end of the parallel circuit and the one end of the corresponding spark gap.

6. A series system of mercury vapor lighting comprising a plurality of spark gaps connected in series, a separate circuit bridged across each spark gap, each separate circuit consisting of a parallel circuit including a mercury vapor lamp and a cut-out bridged across said lamp, and each separate circuit having a resistor connected in series with the parallel circuit between one end of the parallel circuit and one end of the corresponding spark gap, said system having a grounded portion.

7. A series system of mercury vapor lighting having a plurality of units connected in series in a main line and having a substantially constant current high voltage source and having a grounded portion, each unit consisting of a spark gap directly in series with said main line and a parallel circuit bridging said spark gap and connected in series with an impedance with the impedance connected

between one end of the spark gap and one end of the parallel circuit, each of said parallel circuits consisting of a mercury vapor lamp and a bridging cut-out shunted across said lamp for shorting out the lamp upon failure thereof, said spark gap, impedance and cut-out constituting a unitary structure.

8. A unit for a series system of mercury vapor lighting, said unit comprising a mercury vapor lamp and a cut-out shunting said lamp and a spark gap in parallel with said cut-out and lamp and a resistor connected between one side of said spark gap and said lamp and cut-out, said resistor being in series with said lamp and cut-out.

9. A series system of mercury vapor lighting comprising a plurality of mercury vapor lamps connected in series in a main line, a source of high voltage alternating current, a cut-out shunted across each mercury vapor lamp for shorting out any lamp upon failure thereof and constituting a parallel circuit with the corresponding lamp, an impedance connected in series with each mercury vapor lamp and constituting with the mercury vapor lamp and the cut-out a compound circuit, and a spark gap connected in series with said main line and bridging each compound circuit consisting of the series impedance and the parallel circuit.
